CLAIM

The ornamental design for a corner for removable boxes, as shown.

DESCRIPTION

FIG. 1 is a front, top, perspective view of a corner for removable boxes showing our new design;

FIG. 2 is a right side top, perspective view thereof;

FIG. 3 is a rear, bottom, perspective view thereof;

FIG. 4 is a front view thereof;

FIG. 5 is a rear view thereof;

FIG. 6 is a right side view thereof;

FIG. 7 is a left side view thereof;

FIG. 8 is a top view thereof; and,

FIG. 9 is a bottom view thereof.
